UNITED STATES PATENT OFFICE.

THOMAS F. MOORE, OF WINCHESTER, KENTUCKY.

PORTABLE HOIST.

1,081,055.

Specification of Letters Patent.

Patented Dec. 9, 1913.

Application filed October 16, 1912. Serial No. 726,091.

To all whom it may concern:

Be it known that I, THOMAS F. MOORE, a citizen of the United States, residing at Winchester, in the county of Clark and State 5 of Kentucky, have invented certain new and useful Improvements in Portable Hoists; and I do hereby declare the following to be a full, clear, and exact description of the invention, such as will enable others 10 skilled in the art to which it appertains to make and use the same.

My invention relates to improvements in portable cranes, and it consists in the constructions, combinations and arrangements 15 herein described and claimed.

An object of my invention is to provide a portable crane adapted for conveniently loading and unloading cars, wagons, or other vehicles.

20 A further object of my invention is to provide a strong and simple hoisting apparatus constructed to readily and quickly handle loads, and adapted to itself constitute a transporting vehicle.

25 In the accompanying drawings forming a part of this application, and in which similar reference symbols indicate corresponding parts in the several views: Figure 1 is a side elevation, illustrating one embodiment of my invention; Fig. 2 is a front end elevation of the construction shown in Fig. 1; and Fig. 3 is a detail section on the line 3—3 of Fig. 1.

Referring to the drawings, 1 indicates 35 rights secured to a truck 2 and connected by longitudinal members 3 and top cross members 4 to constitute a strong upright frame, said frame being rigidly braced by struts 5 and braces 6.

40 A beam 7 depends from the cross members 4 and is provided with tracks 8 for a trolley carriage 9. The track beam 7 extends rearwardly beyond the upright frame to provide sufficient reach to the crane for 45 conveniently loading and unloading articles; said rearwardly-extending portion being firmly supported by an adjustable truss rod 10 secured to the forward frame member 4 and attached to an end plate 11 having a 50 flange clamped beneath the lower ends of said beam by a bolt 12. A cable, or chain, 13 extends over the sheave 14 of a block 15 carried by the trolley 9, and is anchored to said block 15 to provide a bight for receiving a pulley 16; said pulley 16 being pro-

vided with suitable means for securing the loads, such as hooks 17.

A windlass 18 is mounted on the front uprights 1 for winding and unwinding said cable 13, to raise and lower the loads and 60 to shift the trolley 9 forwardly on its tracks 8; a cam 19 being pivoted on said block 15 for clamping said sheave 14 to prevent raising or lowering of the load during such shifting of the trolley along its tracks 8. 65 The windlass 18 is provided with the usual actuating gearing 18^a and locking pawl 18^b.

As shown in Fig. 1, the cam 19 is adapted to be shifted into clamping engagement with the cable 13 by swinging the front end 70 of said cam downwardly by any suitable means, such as a rope 20 attached thereto and leading in convenient position for operation; upon such shifting of the cam 19, the tension exerted on the cable 13 by the 75 load tends to clamp said cam more firmly in locked position.

The trolley carriage 9 is shifted rearwardly on its tracks 8 by a cable 21 leading therefrom over guide sheaves 22, 23 and 80 24, and secured to a winding arbor 25 journaled at 26 on the front uprights 1; said arbor being provided with a squared end 27 for receiving an operating handle. The arbor is mounted for slight axial shifting in 85 said bearings 26; a toothed collar 28 being secured on said arbor for shifting into locking engagement with a corresponding collar 29 secured to one of said bearings.

I have illustrated and described preferred 90 and satisfactory constructions, but changes could be made within the spirit and scope of my invention.

I claim:—

In a portable crane, the combination of a 95 frame comprising uprights connected by front and rear top cross members, a longitudinal beam secured medially beneath said cross members and projecting rearwardly beyond said frame, a triangular bracket secured on said rear cross member, a truss rod anchored at its respective ends to said front cross member and the projecting end of said beam and bearing on said bracket, parallel track rails secured to the opposite 100 sides of said beam, a trolley carriage on said track rails, guide sheaves secured to the projecting end of said beam and to the front frame uprights, said latter mentioned sheave being located to one side of the 110

track rails to provide a clearance; an intermediate guide sheave supported above said rear cross member, a cable secured to said trolley carriage and extending over said 5 guide sheaves, a winding arbor on the front frame uprights for winding said cable to shift said trolley carriage rearwardly on its tracks, a sheave block carried by said trolley carriage, a cable extending over said 10 sheave block for supporting a load, and a

windlass mounted on said frame for winding said cable to raise and lower the load and to shift the trolley carriage forwardly.

In testimony whereof, I affix my signature, in presence of two witnesses.

THOMAS F. MOORE.
